[57] CLAIM

The ornamental design for a foldable tea cart, as shown and described.

DESCRIPTION

FIG. 1 is a side perspective view of a foldable tea cart showing my new design;

FIG. 2 is a right side elevational view thereof;

FIG. 3 is a left side elevational view thereof, showing the left side leaf in the down position;

FIG. 4 is a rear elevational view thereof, showing the right side leaf in the lowered position;

FIG. 5 is a front elevational view thereof, showing the right side leaf in the lowered position;

FIG. 6 is a bottom plan view thereof, showing the left side leaf in the lowered position;

FIG. 7 is a top plan view thereof, showing the right side leaf in a lowered position;

FIG. 8 is a perspective view thereof, showing the article partially folded; and

FIG. 9 is a perspective view thereof, showing the article completely folded in the closed position.
